[57] CLAIM

The ornamental design for the stacker for electronic copying machine, as shown and described.

DESCRIPTION

FIG. 1 is a top, front and left side perspective view of a stacker for an electronic copying machine showing our new design;

FIG. 2 is a front elevation view thereof;

FIG. 3 is a rear elevation view thereof;

FIG. 4 is a top elevation view thereof;

FIG. 5 is a bottom elevation view thereof;

FIG. 6 is a left side elevation view thereof;

FIG. 7 is a right side elevation view thereof; and,

FIG. 8 is a top, front and left side perspective view thereof, the broken line showing of an electronic copying machine is for illustrative purposes only and forms no part of the claimed design.
